UNITED STATES PATENT OFFICE.

ANTOINE J. LANGELIER, OF PROVIDENCE, RHODE ISLAND.

SWAGING-MACHINE.

SPECIFICATION forming part of Letters Patent No. 542,020, dated July 2, 1895.

Application filed October 13, 1894. Serial No. 525,827. (No model.)

To all whom it may concern:

Be it known that I, ANTOINE J. LANGELIER, a citizen of the United States, and a resident of Providence, in the State of Rhode Island, 5 have invented a new and useful Improvement in Swaging-Machines, of which the following is a specification.

My invention relates to the improved means employed to effect a closing or opening movement of the swaging-dies while the machine is in operation; and it consists in the employment of an angularly-adjustable block and a sliding shoe between the swaging-die and the engaging die-block, as hereinafter fully set 15 forth.

In the accompanying drawings, Figure 1 represents a front elevation of the machine with the front plates removed. Fig. 2 represents a side elevation and a partial section. 20 Fig. 3 represents an axial section of the die-holding spindle, showing a modification. Fig. 4 represents an axial section of the die-holding spindle, showing another modification.

In the drawings, A represents the stationary head, in which is journaled the die-holding spindle B, to which rotary motion is imparted by means of the pulley C. The head A is provided with the beating-rollers a a, which are adapted for engagement with the 25 sliding die-blocks D D to cause the proper reciprocation of the swaging-dies E E, the said engaging die-blocks and swaging-dies being loosely held in the diametrical groove j, made in the enlarged forward end of the 30 holding-spindle B, and between the swaging-dies E and the engaging die-blocks D in the groove j are placed the angularly-adjustable blocks F F, having rounded ends, and provided at their inner rounded ends with a sliding shoe G, by the movement of which the 35 distance between the working faces of the swaging-dies and the engaging die-blocks may be either increased or diminished to the limited extent required.

The enlarged forward end portion of the die-holding spindle B is provided with the perforations b b, adapted to receive the parallel rods c c, which at their forward ends bear against the rear edge of the sliding shoes 45 G, and are secured at their rearward ends to the sliding sleeve H, to which operative connection is made by means of the ring I,

fitting loosely in the circumferential groove d of the sleeve, and connection is made from the ring I to an operative treadle by means 55 of the toggle-jointed arms e e', the arm e being jointed to the ring I by means of the screws f and the arm e' jointed to the bearing-standard g of the head A by means of the screw f', and to the middle joint f'' is attached the 60 downwardly-extending link h, which is connected with the treadle, the said link and treadle being caused to rise by means of a spiral or other suitable spring i, and upon the downward movement of the treadle by 65 the operator of the machine the sleeve H will be thrown forward, thus forcing forward the sliding shoes G and changing the angular position of the adjusting-blocks F F, thus increasing the distance between the swaging- 70 dies E and the engaging die-blocks D, so that the dies will be brought closer together upon the engaging impulse of the beating-rollers a. The several parts are held in position in the groove j of the die-holding spindle by means 75 of the face-plate J which is secured to the front face of the spindle by means of screws, and the reverse movement is imparted to the sliding shoes G by means of the springs l, secured to the front of the face-plate J, which 80 springs act upon the projecting forward ends of the said shoes.

A modification of my invention is shown in Fig. 3, in which the sliding shoes G are shown at the outer instead of the inner end of the 85 angularly-adjustable blocks F F, and in this case the desired movement of the shoes is produced by means of the bell crank levers m, which are connected by means of the links n with the rods c, which rods are connected 90 with the sliding sleeve H, and upon the forward movement of the sleeve H the swaging-dies will be brought closer together, as before.

Another modification is shown in Fig. 4, in 95 which the angularly-adjustable blocks F F are provided with a rearwardly-extending arm k, to which the links n are connected, and in this case the springs l for operating the shoes in the reverse direction are dispensed with, 100 the said angularly-adjustable blocks being positively connected with the sleeve H, so as to be operated thereby in both directions.

I claim as my invention—

1. In a swaging machine, the combination of the beaters, the swaging dies, and the engaging die-blocks, with the angularly adjustable blocks, and means for changing the direction of the axes of the adjustable blocks while the machine is in operation, substantially as described.
2. In a swaging machine, the combination of the stationary head, and the beating rollers, with the rotary spindle provided with the

engaging die-blocks, the swaging dies, the angularly adjustable blocks, the slidable shoes, and means for changing the direction of the axes of the adjustable blocks, while the machine is in operation, substantially as described. 15

ANTOINE J. LANGELIER.
